United States Patent Office

Des. 182,865
Patented May 20, 1958

182,865

SIGN BOARD

Charles D. Winters, Sr., Belmar, N. J., assignor to Gertrude P. Winters, Belmar, N. J.

Application February 17, 1956, Serial No. 40,208

Term of patent 14 years

(Cl. D1—12)

FIG. 2

The dominant features of my design reside in the full line portion of the drawing. The rear of the sign is substantially plain.

I claim:

I claim:
The ornamental design for a sign board, as shown and described.
